CLAIM

The ornamental design for a shirt, as shown and described.

DESCRIPTION

FIG. 1 is a front, side perspective view of a shirt;

FIG. 2 is a rear, side perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines depict portions of the shirt that form no part of the claimed design.

1 Claim, 5 Drawing Sheets
